WORK-POSITIONING MECHANISM

Neil J. Ranney, Euclid, Ohio, assignor to Wean Equipment Corporation, Euclid, Ohio, a corporation of Ohio

Filed Sept. 10, 1952, Ser. No. 308,880

26 Claims. (Cl. 90—59)

This invention relates to work-positioning mechanisms and particularly to a mechanism for positioning work for machining at successive work stations. There has long been a need for a mechanism for carrying and positioning heavy and odd-shaped workpieces from one to another of successive work stations where machining is done upon the workpiece without the need for setting up the workpiece for each work station. I have embodied the invention in an apparatus for positioning hollow objects such as metal hulls and have illustrated and described hereafter an apparatus particularly adapted to that purpose.

I provide generally a track leading to a machining station, ways at the machining station generally alongside the track, a work carrier movable along the track to the machining station and means for transferring the carrier from the track to the ways at the machining station to accurately position the work carried by the carrier for machining.

Preferably the work carrier is provided with portions overhanging the ways when the car is on the tracks and with means for retracting the wheels upwardly relatively to the carrier until the overhanging portion engages the ways. In a preferred form the wheels are mounted on eccentric means and means are provided on the carrier for turning the eccentric means to retract the wheels upwardly. At least one of the ways is preferably provided with downwardly diverging positioning portions engaging similar portions on the corresponding overhanging portion of the work carrier. The other way preferably has a substantially plane horizontal face for supporting engagement with the carrier. The carrier is preferably self-propelled for moving along the track into approximately the proper position lengthwise of the track at a machining station. Means are provided at the machining station for moving the carrier slightly in the direction lengthwise of the track into precisely the proper position in that direction for machining at the station. Preferably the means for moving the carrier at the machining station comprises means movable generally in a plane normal to the direction lengthwise of the track having a portion entering between opposed vertical surfaces on the carrier normal to the direction lengthwise of the track. The portion entering between the vertical surfaces on the carrier is preferably provided with a tapered nose and a following part of substantially constant dimension in the direction lengthwise of the track having a close guiding fit between the vertical surfaces of the carrier so that when the tapered nose moves into engagement with one or the other of the vertical surfaces it moves the carrier slightly in the direction lengthwise of the track into precisely the proper position in that direction for machining at the machining station and the following part of substantially constant dimension holds the carrier in that position during machining.

The carrier itself is preferably provided with means receiving the workpiece to be machined and means for accurately positioning it relative to the work carrier. The means receiving the work is preferably resiliently mounted

2

to automatically adjust to irregularities in the surface of the workpiece. In a preferred form the means receiving the work comprises a plurality of hollow vertical sockets mounted on the work carrier in spaced-apart relation. A piston is provided in each socket for movement therein. Spring means are mounted on each piston tending to move the piston vertically upwardly in its socket. Work-engaging means are provided on one end of the carrier for engaging one end of the workpiece. This work-engaging means is arranged to permit rotation on a horizontal axis and is movable horizontally in the direction of the axis of rotation. A second work-engaging means is mounted on the carrier at the opposite end of the workpiece and engages the opposite end for movement vertically and horizontally. Preferably the second work-engaging means includes a rear locating and support plate fixed in an opening in the hull to be machined and a pair of vertical pedestals movable vertically and horizontally by screw means to adjust the hull on the carrier. The relative amount of adjustment of each of the first work-engaging means and the second work-engaging means is regulated with respect to a gauging and set-up means more fully discussed hereafter.

Locking means are provided on the resilient means engaging a bevel surface thereon to limit the downward movement of the resilient means after the workpiece has been properly positioned on the work carrier.

Gauging and step-up means are provided on the carrier for regulating the positioning of the workpiece thereon and determining the extent of movement of the two work-engaging means.

Means are preferably provided at the work station for engaging the workpiece against the work-receiving means on the carrier to maintain the work against movement relative to the carrier during machining. This may be a plurality of spaced-apart hydraulic pistons suspended above the track at the work station and acting generally downwardly to tightly engage the workpiece against the end of the work-receiving pistons.

I have attempted to point out particular features of my invention and their advantages but have not attempted to detail each and every one of the novel features thereof. Other details, features and advantages of my invention will become apparent from the following description of a present preferred embodiment thereof.

In the accompanying drawings I have shown a present preferred embodiment of apparatus including the above-outlined apparatus features in which

Figure 46 is an end elevation of a rear supporting plate engaging the workpiece;

Figure 47 is a schematic drawing of the hydraulic system operating the various members at the work station.

Referring to the drawings I have illustrated a work carrier having a frame 10 carrying a bedplate 11. A series of spaced-apart hollow vertical sockets 12 are mounted on the bedplate 11 (see Figures 1—5). Each of these sockets is provided with a cylindrical piston 13 vertically movable therein (Figure 36). A compression spring 14 rests on the socket 12 and engages the piston 13 tending to raise it vertically in the socket. The end 15 of the piston which extends out of the vertical socket 12 is rounded to form a hemispherical supporting surface upon which the work 16 to be machined is placed. The opposite end of the piston 13 is provided with a beveled face 17 which faces an opening 18 in the wall of the vertical socket 12. The beveled face is maintained in this position by a threaded keeper 19 which operates in a keyway 20 in the sidewall of the piston thus limiting the rotary movement of the piston in the socket 12 (Figures 37—38). A stop or locking member 21 is slidably mounted in the opening 18 to project into the interior of the socket 12 (Figure 36). The end of the locking member 21 entering into the socket is provided with a beveled face 22 which engages the beveled face 17 of the movable piston 13 to limit its movement downwardly. A threaded keeper 23 rides in a slot 24 in the side of the locking member 21 thereby maintaining the bevel face 22 in proper position to engage the bevel of the piston. The position of the stop or locking member 21 is fixed by a regulating screw 25 which abuts the end of the member opposite the bevel face 22.

A pair of spaced-apart supporting pedestals 26 are fastened to the bedplate 11 of the carrier near the front of the carrier (Figures 1, 2, 3, 9—14). Each of the pedestals 26 is provided with a saddle 27 adapted to receive a rotatable member 28, more fully described hereafter. A clamping member 29 is journaled intermediate its ends to the rear of each of the supporting pedestals. One end of the clamping member 29 is provided with a clamping jaw 30 adapted to engage the rotatable member 28 and hold it in the saddle 27. The opposite end of the clamping member 29 is pivotally connected to a feed screw 31 threadingly engaging a nut 32 provided with stub shafts 33 adapted to removably engage slots 34 in a journal block 35 on the base of the supporting pedestal.

The rotatable member 28 is made up of a hollow cylindrical member 36 terminating at either end in shaft portions 37 adapted to rest upon the saddles 27 of the supporting pedestals 26. One of the shaft portions 37 terminates in a fixed bearing shoulder 38. The other shaft portion is provided with a movable bearing shoulder 39 threaded into a socket 40 therein. The movable bearing shoulder 39 is provided with an opening 41 adapted to receive a turning crank 42 by means of which the movable shoulder can be threaded into or out of the socket 40 to shorten or elongate the rotatable member 28. The two bearing shoulders 38 and 39 bear against bearing pads 43 in end plates 44 which are bolted to cross drive openings 45 in the hull 16 to be supported. Each of the end plates 44 is provided with a flush pin gauge 46 and a positioning screw 47. The flush pin gauge acts to contact an indexing pad 48 and the positioning screw to contact a shoulder 49 both on the supporting pedestal in order to determine the proper positioning of the hull 16 on the car in the direction axially of the rotatable supporting member 28.

A second pair of spaced-apart supporting pedestals 50 are fastened to the bedplate 11 of the carrier near the rear of the carrier (Figures 1, 2, 6—8). Each of these pedestals is provided with a vertical jack 51 and with a horizontal jack 52. The two horizontal jacks 52 are mounted so as to operate toward the center line of the bedplate 11 and accordingly toward one another. A horizontal table 53 is mounted on each pedestal 50 alongside

the path of travel of the vertical jack 51. A spring-loaded yoke 54 on each pedestal is vertically movable on a shaft 55 between the vertical jack 51 and the table 53. One arm of the yoke extends over the vertical jack and has a contact pad 56 on the center line of the vertical jack 51. The other arm of the yoke extends over the table 53 and has a similar contact pad 57 which contacts the upper surface of the table. The yoke 54 is preferably slotted in order to permit adjusting the pads 56 and 57 to properly position them over the jack 51 and the table 53. A rear locating and support plate 59 is fixed in an opening 60 at the rear of the hull 16. A pair of hangers 61 extend from the support plate 59 and engage the surface of the hull above the opening 60. Spring-loaded yokes 62 are provided on the support plate, one arm of each yoke engaging the inner side of an inner member 63 of the hull and the other arm resting upon a spacer member 64. A second set of yokes 65 are located at the bottom of the support plate. One arm of each of the yokes 65 engages the exterior surface of the rear hull plate adjacent the edge of the opening 60 and the other arm bears on the support plate itself. The yokes 62 tend to draw the plate 59 into the opening 60 causing the second set of yokes 65 and an abutting portion 66 of the hanger arms to bear against the bottom and the top respectively of the rear hull plate to resist the pull of yokes 62. A pair of tightening screws 67 on the base of the supporting plate bear against the edge of the hull 16 tending to draw the hanger arms 61 into tight engagement with the top of the hull. One edge of the supporting plate 59 is provided with an angular surface 68 upon which a wedge 69 rides. The wedge 69 is slotted to move vertically on a tightening bolt 70 fixed to a back-up plate 71 welded or otherwise fastened to the supporting plate adjacent the angular surface 68. The wedge 69 is forced downwardly between the angular surface 68 and the edge of the opening 60 in the hull, wedging the opposite edge 72 of the support plate 59 into tight engagement with the edge of the opening 60. A pair of supporting arms 73 extend rearward from the supporting plate 59 and rest upon the top of the vertical jack 51 and beneath the contact pad 56 of the yoke 54. A spacer 74 substantially equal in thickness to the thickness of supporting arms 73 is placed upon the table 53 beneath the contact pad 57 of the yoke 54 to equalize the yoke pressure in the downward direction. Vertical movement of the hull 16 about the rotatable member 28 previously described is controlled by controlling the movement of the vertical jacks 51 against the supporting arms 73. A horizontally extending arm 75 projects rearwardly from the support plate 59 on substantially the center line of the horizontal jack 52 and between them. Both horizontal jacks 52 bear on the arm 74 to regulate the horizontal movement of the hull 16 on the carrier.

A gauging and set-up beam 76 is removably mounted lengthwise of the carrier alongside the hull 16 on spaced-apart supporting bases 77 and 78 (Figures 16-19). Each of the bases 77 and 78 is indexed on the carrier by means of an indexing key 79 and the beam 76 is indexed on the bases 77 and 78 by guide plates 80 fixed to the base of the beam and engaging a keyway 81 in the top of each base. A dovetail way 82 fixed in a slot 83 in the top of the gauging and set-up beam extends lengthwise along the beam interrupted, however, by a cut-away portion 84 intermediate its ends for convenient access with gauging and set-up devices to be hereafter described.

The vertical positioning of the rear supporting and positioning plate 59 is determined by a spring-loaded target pin 85 mounted on the end of a removable carrier arm 86 slideable on the dovetail way 82 on the indexing beam (Figures 21-23). The carrier arm 86 is held in position on the way 82 by one edge of a dovetailed base 87 and a moving wedge 88 therein which engages the side of the way farthest removed from the work. The wedge 88 is caused to move by a hand wheel 89 threaded

in the side of the carrier arm base 87. The rear supporting plate is moved upwardly or downwardly as the case may be by the vertical jacks 51 until the head 90 of the target pin 85 will enter into an index opening 91 in a centering plate 92 fixed to the hull 16. The horizontal positioning of the rear supporting and positioning plate 59 is determined by a flush pin gauge 93 on the carrier arm alongside the target pin 85. The flush pin gauge acts against a surface on the centering plate 92 and the supporting plate 59 is moved by the horizontal jacks 52 until the positioning of the flush pin gauge 93 against the centering plate is correct.

Other gauging and set-up means may also be used on the gauging and set-up beam for various purposes. For example, in Figures 24 through 26 I show a slope gauge 94 and surface gauge 95 for determining the position and amount of milling around an opening 96 in the hull 16 over which a cover plate is subsequently to be bolted. The slope gauge 94 is made up of a base 97 which runs on the dovetail way 82 on the gauging and set-up beam and like the carrier arm 86 is held in fixed position therein by a wedge and hand wheel 98 arrangement. An outboard slope indexing member 99 extends outwardly from the base 97 and provides a surface of proper slope for controlling the milling of the edge of opening 96 in the hull. The surface gauge 95 is made up of a carrier arm 100 mounted on a base 101 which runs on the dovetail way 82 on the gauging and set-up beam and is held in selected fixed position thereon by a wedge and hand wheel 102 in the same manner as carrier arm 86 previously described. A flush pin gauge 103 is mounted in the end of the carrier arm 100 to bear on the machined edge of the opening 96 to determine the extent of milling necessary to bring the surface within the required tolerances with respect to the surface of the hull.

An axle 104 is journaled eccentrically in journal boxes 105 mounted beneath the frame 10 (Figures 4, 5, 15). Flanged wheels 106 are mounted on the axle for rotation about the axle on roller bearings 107 (Figure 15). A hydraulic piston 108 is attached to a crank arm 109 intermediate the ends of axle 104 for rotating the axle 104 eccentrically in the journal 105 to raise and lower the bottom of the flanged wheels 106 with respect to the bedplate 11 of the carrier (Figure 27). A stop arm 110 extends opposite the crank arm on the axle shaft to contact a portion of the frame to hold the wheels in position when lowered the maximum distance away from the bedplate 11. The front pair of wheels 106 are provided with gears 111 keyed thereto by means of a key 112 or similar means (Figure 15). Each of the gears 111 is driven from a similar toothed gear 113 mounted on a jack shaft 114 which is journaled on a frame parallel to the axle 104 (Figure 3). The two gears 111 and 113 are connected by a sprocket chain 115 which is provided with a spring-loaded keeper 116 in order to provide the necessary slack for rotating the wheels on the eccentric axle to raise and lower them relative to the bedplate 11 of the carrier. One end of the jack shaft 114 is provided with a pair of toothed gears 117 which are connected by means of a sprocket chain 118 to a similar toothed gear 119 driven by a hydraulic motor 120 (Figure 28). The flanged wheels 106 run on a track rail 121 which passes from one machining station to another and the carrier is driven by the hydraulic motor 120 from the loading station to each successive machining station on these tracks. At each machining station there is provided a plurality of positioning elements each of which is made up of an indexing clamp member 122, generally in the form of a bell crank, rotatable on a shaft 123 extending between two upwardly extending side arms 124 (Figures 31, 32). One arm of the clamp member is connected to a hydraulic cylinder 125 which acts to rotate the clamp member about the shaft 123. The opposite end of the clamp member 122 is provided with a wedge-shaped nose 126 which is adapted to enter between two vertical and substantially

parallel guide pads 127 mounted in a bracket 128 on the overhanging portion 129 of the carrier (Figures 31-35). When the carrier is moved to the machining station the hydraulic piston 125 is actuated to move the wedge-shaped nose of the clamping member between the vertical pads 127. This moves the carrier longitudinally of the track to generally position it at the machining station. When this is completed a cam member 130 releases a switch 131 which lights a warning light or otherwise warns the operator that the carrier is in position at the machining station. The hydraulic cylinder which operates the eccentric axles on the carrier is then operated to rotate the wheels upwardly towards the bed-plate 11 of the carrier. This lowers the carrier toward the track and onto an inverted V-shaped way 132 positioned beside and substantially parallel to the rails 121 (Figures 3-6, 32). The V-shaped way 132 engages a V-groove supporting member 133 on the overhanging portion 129 of the carrier to position the carrier transversely of the track with respect to the machining station. The opposite side of the carrier is provided with a flat supporting member 133a which simultaneously engages a flat way 132a parallel to the V-shaped way and on the opposite side of the tracks. As the carrier is lowered into position on the ways it engages a switch 134 which indicates either visually or audibly that the carrier is on or approaching the ways 132 and 132a (Figure 32). The clamping member 122 is then actuated to follow the downward movement of the carrier to maintain it properly positioned on the tracks. When the carrier is entirely supported by the ways the nose 126 of the clamping member 122 is forced into tight engagement with a pad 135 at the bottom of the two vertical guide pads 127 thereby clamping the frame of the carrier against the guideways. When the clamping member has reached its clamping position on the pad 135 a switch 136 acting on a cam 137 on the shaft 123 of the clamping member indicates to the operator that the clamping member is in position on the pad. In order to permit the ways 132 to be properly positioned at the machining station they are supported on wedge-shaped blocks 138 which slide one upon the other in the usual manner to raise or lower the V-way as the need may be. The ultimate position of the wedge blocks 138 is maintained by locking screws 139 in the ordinary manner.

The hydraulic power for operating the hydraulic motor 120 which furnishes the motive power for the carrier and for operating the hydraulic piston 108 which rotates the eccentric axle 104 is supplied by an electric motor 140 and hydraulic pump 141 located at the front end of the carrier (Figures 40-42). The electrical current for the electric motor 140 is picked up by a spring-loaded shoe 142 which rides on a power rail 143 between the load-bearing rails and beneath the central portion of the carrier (Figure 29). The power rail is supported by spaced-apart brackets 144 and insulators 145 in the usual manner. A sloping shield or shoulder 146 is provided both at the beginning of the machining line and at the end of the machining line to guide the spring-loaded shoe 142 onto and off of the power rail 143 when the carrier is lifted from the rails at the end of the machining run and returned to the rails at the loading station. The circuit through the electric motor from the power rail 143 is completed by a second spring-loaded shoe 147 which rides on the load-bearing rail 121. A seat 148 is provided adjacent the electric motor 140 and the hydraulic pump 141 from which the operator may control the starting and stopping switches 149 for the electric motor and the hydraulic valves 150 and 151 which control the hydraulic motor 120 and the hydraulic pistons 108 (Figures 40-42).

When the carrier has been lowered onto the ways 132 at a machining station and clamped by the clamping member 126, a set of hydraulic pistons 152 (Figures 43-44) may be brought to bear against the top of the work-

piece or hull 16 to hold it tightly against the resiliently mounted pistons 15 on the carrier to prevent shifting of the hull during heavy machining operations as for example, milling a portion of the hull surface with end mills such as those shown in Figure 45 and identified by the numeral 153. The pistons 152 are preferably suspended on an overhead bridge structure 154 which extends over the rails at the machining station.

The hydraulic system which controls the operation of the carrier clamping member 126, the overhead pistons 152, and the movement of the machining tool 153 is shown diagrammatically in Figure 47. This system is controlled by an operator preferably located at the machining station. In the diagram the power is supplied by an electric motor 155 which drives a hydraulic pump 156 which in turn supplies hydraulic fluid to the system. The hydraulic fluid is carried through the usual piping system 157 including pressure gauges 158, pressure reducing valves 159, solenoid valves 160 and hydraulic switches 161, all operated to control the flow of fluid to the hydraulic cylinder 125 operating the clamp member 126, the hydraulic cylinder 152 of the overhead bridge and the vertical travel cylinders 162 on the milling head 153.

While I have shown and described a present preferred embodiment of the invention it is to be understood that the invention is not limited thereto but may be otherwise embodied within the scope of the following claims.

I claim:

1. Mechanism for positioning work for machining comprising a track leading to a machining station, a work carrier movable along the track to the machining station, ways at the machining station generally alongside the track, one of the ways extending generally parallel to the track and having downwardly diverging positioning portions to position the carrier in proper position transversely of the track for machining at the machining station upon relative generally vertical movement of the ways and carrier, another of the ways having a substantially plane horizontal face for supporting engagement with the carrier, and means for relatively generally vertically moving the ways and carrier to position the carrier by the ways and remove the carrier from the track.
2. Mechanism for positioning work for machining comprising a track leading to a machining station, a work carrier movable along the track to the machining station, ways at the machining station generally alongside the track, means for relatively generally vertically moving the ways and carrier to position the carrier by the ways and remove the carrier from the track, the carrier and at least one of the ways having cooperating means positioning the carrier in proper position transversely of the direction of the length of the track for machining at the machining station, and means mounted at the machining station for positioning the carrier in proper position in the direction lengthwise of the track for machining at the machining station.
3. Mechanism for positioning work for machining comprising a track leading to a machining station, a work carrier movable along the track to the machining station, means for moving the carrier along the track into approximately the proper position in the direction lengthwise of the track for machining at the machining station, the carrier having opposed vertical surfaces lying generally in parallel planes normal to the direction lengthwise of the track, and means mounted at the machining station movable generally in a plane normal to the direction lengthwise of the track and having a portion entering the space between said opposed surfaces, said portion having a tapered nose and a following part of substantially constant dimension in the direction lengthwise of the track having a close guiding fit between said opposed surfaces so that when said tapered nose moves into engagement with one or the other of said opposed surfaces it moves the carrier slightly in the direction lengthwise of the track into precisely the proper position in that direction.

for machining at the machining station, and when said following part moves into guiding relationship with said opposed surfaces it holds the carrier in said last mentioned position.

4. Mechanism for successively positioning a workpiece at spaced-apart work stations comprising a track passing through each of successive work stations, ways at each work station generally parallel to the track on opposite sides thereof, a self-propelled work-carrying car having a body, drive means on the carrier propelling said carrier, eccentric means on the body and wheels rotatably mounted on the eccentric means and adapted to run on the track, said body having a portion overhanging the ways and spaced above them when the wheels are in running position on the track, drive means turning the eccentric means on the body to retract the wheels upwardly relative to the body when the car is at a work station and positioning means acting simultaneously with the turning means accurately positioning the overhanging portion of the body on the ways as the wheels are retracted.

5. Mechanism for successively positioning a workpiece at spaced-apart work stations comprising a track passing through each of successive work stations, ways at each work station generally parallel to the track on opposite sides thereof, a self-propelled work carrying car having a body and wheels adapted to run on the track, drive means on the carrier propelling said carrier, said body having a portion overhanging the ways and spaced above them when the wheels are in running position on the track, hydraulic piston means retracting the wheels upwardly relative to the car body to lower the overhanging portion of the body into contact with the ways, guide means on the carrier having opposed substantially parallel vertical surfaces normal to the length of the track and forming a guideway, and positioning means at each work station having a tapered portion movable in a plane substantially parallel to the vertical surfaces on the carrier and entering therebetween, whereby the carrier is moved lengthwise of the track into precise position for machining at the work station.

6. Mechanism for positioning work for machining comprising a track leading to a machining station, a work carrier movable along the track to the machining station, a plurality of hollow vertical sockets mounted on the work carrier, a piston in each of said sockets, each piston having a bevel face thereon, spring means on each piston tending to move it vertically upwardly in its socket, said pistons receiving the work to be machined and automatically adjusting against the spring means to irregularities in the workpiece, positioning means on the carrier accurately positioning the work relative to the work carrier, locking means on each socket engaging the bevel face on the piston therein limiting the downward movement of the piston after the work is positioned relative to the carrier and means at the machining station accurately positioning the work carrier with respect thereto.

7. Mechanism for positioning work for machining comprising a track leading to a machining station, a work carrier movable along the track to the machining station, resilient means on the carrier receiving the work to be machined to automatically adjust to irregularities in the surface of the workpiece, work-engaging means on the carrier engaging one end of the workpiece for rotation on a horizontal axis, said work-engaging means being positively driven in the direction of the axis of rotation to position said one end of the workpiece on the carrier, a second work-engaging means on the carrier at the opposite end of the workpiece engaging the workpiece for movement vertically and horizontally, and positioning means at the machining station accurately positioning the work carrier with respect thereto.

8. Mechanism for positioning work for machining comprising a track leading to a machining station, a work carrier movable along the track to the machining station,

resilient means on the carrier receiving the work to be machined to automatically adjust to irregularities in the surface of the workpiece to support the workpiece, work-engaging means on the carrier engaging one end of the workpiece for rotation on a horizontal axis, screw means cooperating with the work-engaging means to move the work-engaging means in the direction of the axis of rotation to position the workpiece on the carrier, a second work-engaging means on the carrier at the opposite end of the workpiece engaging the workpiece, second screw means cooperating with the second work-engaging means, moving said second work-engaging means vertically and horizontally, and positioning means at the machining station accurately positioning the work carrier with respect thereto.

9. Mechanism for positioning work for machining comprising a track leading to a machining station, a work carrier movable along the track to the machining station, resilient means on the carrier receiving the work to be machined to automatically adjust to irregularities in the surface of the workpiece to support the workpiece, work-engaging means on the carrier engaging one end of the workpiece for rotation on a horizontal axis, screw means cooperating with the work-engaging means to move the work-engaging means in the direction of the axis of rotation to position the workpiece on the carrier, a second work-engaging means on the carrier at the opposite end of the workpiece engaging the workpiece, second screw means cooperating with the second work-engaging means, moving said second work-engaging means vertically and horizontally, locking means on the resilient means engaging the resilient means and limiting the movement of the resilient means upon completion of the movement of the work-engaging means, and positioning means at the machining station positioning the work carrier with respect thereto.

10. Mechanism for positioning work for machining comprising a track leading to a machining station, a work carrier movable along the track to the machining station, resilient means on the carrier receiving the work to be machined to automatically adjust to irregularities in the surface of the workpiece to support the workpiece, work-engaging means on the carrier engaging one end of the workpiece for rotation on a horizontal axis, said work-engaging means being adjustable in the direction of the axis of rotation to position said one end of the workpiece on the carrier, a second work-engaging means on the carrier at the opposite end of the workpiece engaging the workpiece for movement vertically and horizontally, removable gauging and set-up means on the carrier determining the movements of the two work-engaging means, and positioning means at the machining station accurately positioning the work carrier with respect thereto.

11. Mechanism for positioning work for machining comprising a track leading to a machining station, a work carrier movable along the track to the machining station, resilient means on the carrier receiving the work to be machined to automatically adjust to irregularities in the surface of the workpiece to support the workpiece, work-engaging means on the carrier engaging one end of the workpiece for rotation on a horizontal axis, said work-engaging means being adjustable in the direction of the axis of rotation to position said one end of the workpiece on the carrier, a second work-engaging means on the carrier at the opposite end of the workpiece engaging the workpiece for movement vertically and horizontally, removable horizontally extending guide means on the carrier substantially normal to the axis of rotation of the workpiece at the first work-engaging means, removable gauging and set-up means on the horizontally extending guide means determining the movements of the two work-engaging means, and positioning means at the machining station accurately positioning the work carrier with respect thereto.

12. Mechanism for positioning work for machining

comprising a track leading to a machining station, a work carrier movable along the track to a machining station, resilient means on the work carrier receiving the work to be machined and automatically adjusting to irregularities in the surface of the workpiece to support the workpiece, means on the carrier accurately positioning the work relative to the work carrier, locking means on the resilient means limiting the movement of the resilient means after the work is positioned on the carrier, means at the machining station accurately positioning the work carrier with respect to the work station, and work-clamping means at the machining station engaging the workpiece to force the workpiece against the resilient means thereby maintaining the work against movement relative to the work station during machining.

13. Mechanism for positioning work for machining comprising a track leading to a machining station, a work carrier movable along the track to the machining station, a plurality of hollow vertical sockets mounted on the work carrier, a piston in each of said sockets, each piston having a bevel face thereon, spring means on each piston tending to move it vertically upwardly in its socket, said pistons receiving the work to be machined and automatically adjusting against the spring means to irregularities in the workpiece, work-engaging means on the carrier engaging one end of the workpiece for rotation on a horizontal axis, screw means cooperating with the work-engaging means to move the work-engaging means in the direction of the axis of rotation to position the workpiece on the carrier, a second work-engaging means on the carrier at the opposite end of the workpiece engaging the workpiece, second screw means cooperating with the second work-engaging means moving said second work-engaging means vertically and horizontally, locking means on each vertical socket engaging the bevel face on the piston limiting the downward movement of the piston after the work is positioned relative to the carrier, positioning means at the work station accurately positioning the work carrier with respect thereto, and hydraulic piston means suspended above the track at the work station engaging the workpiece against the work-receiving pistons after the work carrier is positioned to maintain the workpiece against movement relative to the work carrier during machining.

14. Mechanism for positioning work for machining comprising a track leading to a machining station, a work carrier movable along the track to the machining station, resilient means on the carrier receiving the work to be machined and automatically adjusting to irregularities in the surface of the workpiece, means on the carrier accurately positioning the work relative to the work carrier, means limiting the position of the resilient means after the positioning of the work relative to the ways at the machining station generally alongside the track, at least one of the ways extending generally parallel to the track and having downwardly diverging positioning portions to position the carrier in proper position transversely of the track for machining at the machining station upon relative generally vertical movement of the ways and carrier, and means for relatively generally vertically moving the ways and carrier to position the carrier by the ways and remove the carrier from the track.

15. Mechanism for positioning work for machining comprising a track leading to a machining station, a work carrier movable along the track to the machining station, resilient means on the carrier including a piston having a bevel face thereon, said resilient means receiving the work to be machined and automatically adjusting to irregularities in the surface of the workpiece, means on the carrier accurately positioning the work relative to the work carrier, locking means on the resilient means engaging the bevel face on said piston and limiting the movement of the resilient means after positioning the work relative to the carrier, ways at the machining station generally alongside the track, one of the ways extending generally paral-

lel to the track and having downwardly diverging positioning portions to position the carrier in proper position transversely of the track for machining at the machining station upon relative generally vertical movement of the ways and carrier, another of the ways having a substantially plane horizontal face for supporting engagement with the carrier, and means for relatively generally vertically moving the ways and carrier to position the carrier by the ways and remove the carrier from the track.

16. Mechanism for positioning work for machining comprising a track leading to a machining station, a work carrier movable along the track to the machining station, a plurality of hollow vertical sockets mounted on the work carrier, a piston in each of said sockets, each piston having a bevel face thereon, spring means on each piston tending to move it vertically upwardly in its socket, said pistons receiving the work to be machined and automatically adjusting against the spring means to irregularities in the workpiece, means on the carrier accurately positioning the work relative to the work carrier, locking means on each socket engaging the bevel face on the piston therein limiting the downward movement of the piston after the work is positioned relative to the carrier, ways at the machining station generally alongside the track, means for relatively generally vertically moving the ways and carrier to position the carrier by the ways and remove the carrier from the track and means mounted at the machining station for positioning the carrier in proper position in the direction lengthwise of the track for machining at the machining station.

17. Mechanism for positioning work for machining comprising a track leading to a machining station, a work carrier movable along the track to the machining station, resilient means on the carrier receiving the work to be machined to automatically adjust to irregularities in the surface of the workpiece, work-engaging means on the carrier engaging one end of the workpiece for rotation on a horizontal axis, said work-engaging means being positively driven in the direction of the axis of rotation to position said one end of the workpiece on the carrier, a second work-engaging means on the carrier at the opposite end of the workpiece engaging the workpiece for movement vertically and horizontally, ways at the machining station generally alongside the track and means for relatively generally vertically moving the ways and carrier to position the carrier by the ways and remove the carrier from the track, the carrier and at least one of the ways having cooperating means positioning the carrier in proper position transversely of the direction of the length of the track for machining at the machining station.

18. Mechanism for positioning work for machining comprising a track leading to a machining station, a work carrier movable along the track to the machining station, resilient means on the carrier receiving the work to be machined to automatically adjust to irregularities in the surface of the workpiece to support the workpiece, work-engaging means on the carrier engaging one end of the workpiece for rotation on a horizontal axis, screw means cooperating with the work-engaging means to move the work-engaging means in the direction of the axis of rotation to position the workpiece on the carrier, a second work-engaging means on the carrier at the opposite end of the workpiece engaging the workpiece, second screw means cooperating with the second work-engaging means, moving said second work-engaging means vertically and horizontally, ways at the machining station generally alongside the track, means for relatively generally vertically moving the ways and carrier to position the carrier by the ways and remove the carrier from the track, the carrier and at least one of the ways having cooperating means positioning the carrier in proper position transversely of the direction of the length of the track for machining at the machining station, and means mounted at the machining station for positioning the carrier in

proper position in the direction lengthwise of the track for machining at the machining station.

19. Mechanism for positioning work for machining comprising a track leading to a machining station, a work carrier movable along the track to the machining station, resilient means on the carrier receiving the work to be machined to automatically adjust to irregularities in the surface of the workpiece to support the workpiece, work-engaging means on the carrier engaging one end of the workpiece for rotation on a horizontal axis, screw means cooperating with the work-engaging means to move the work-engaging means in the direction of the axis of rotation to position the workpiece on the carrier, a second work-engaging means on the carrier at the opposite end of the workpiece engaging the workpiece, second screw means cooperating with the second work-engaging means, moving said second work-engaging means vertically and horizontally, locking means on the resilient means engaging the resilient means and limiting the movement of the resilient means upon completion of the movement of the two work-engaging means, ways at the machining station generally alongside the track, and means for transferring the carrier from the track to the ways at the machining station to accurately position the work carried by the carrier for machining.

20. Mechanism for positioning work for machining comprising a track leading to a machining station, a work carrier movable along the track to the machining station, resilient means on the carrier receiving the work to be machined to automatically adjust to irregularities in the surface of the workpiece to support the workpiece, work-engaging means on the carrier engaging one end of the workpiece for rotation on a horizontal axis, said work-engaging means being adjustable in the direction of the axis of rotation to position said one end of the workpiece on the carrier, a second work-engaging means on the carrier at the opposite end of the workpiece engaging the workpiece for movement vertically and horizontally, removable indexing means on the carrier determining the movements of the two work-engaging means, means for moving the carrier along the track into approximately the proper position in the direction lengthwise of the track for machining at the machining station and means mounted at the machining station for moving the carrier slightly in the direction lengthwise of the track into precisely the proper position in that direction for machining at the machining station.

21. Mechanism for positioning work for machining comprising a track leading to a machining station, a work carrier movable along the track to the machining station, resilient means on the carrier receiving the work to be machined to automatically adjust the irregularities in the surface of the workpiece to support the workpiece, work-engaging means on the carrier engaging one end of the workpiece for rotation on a horizontal axis, said work-engaging means being adjustable in the direction of the axis of rotation to position said one end of the workpiece on the carrier, a second work-engaging means on the carrier at the opposite end of the workpiece engaging the workpiece for movement vertically and horizontally, removable horizontally extending guide means on the carrier substantially normal to the axis of rotation of the workpiece at the first work-engaging means, removable indexing means on the horizontally extending guide means determining the movements of the two work-engaging means, means for moving the carrier along the track into approximately the proper position in the direction lengthwise of the track for machining at the machining station and means mounted at the machining station for moving the carrier slightly in the direction lengthwise of the track into precisely the proper position in that direction for machining at the machining station, said last mentioned means comprising a member movable transversely of the direction of the length of the track into engagement with the carrier adapted to interfit with the carrier.

22. Mechanism for positioning work for machining comprising a track leading to a machining station, a work carrier movable along the track to a machining station, means on the work carrier receiving the work to be machined and accurately positioning it relative to the work carrier, means for moving the carrier along the track into approximately the proper position in the direction lengthwise of the track for machining at the machining station, the carrier having opposed vertical surfaces lying generally in parallel planes normal to the direction lengthwise of the track, and means mounted at the machining station movable generally in a plane normal to the direction lengthwise of the track and having a portion entering the space between said opposed surfaces, said portion having a tapered nose and a following part of substantially constant dimension in the direction lengthwise of the track having a close guiding fit between said opposed surfaces so that when said tapered nose moves into engagement with one or the other of said opposed surfaces it moves the carrier slightly in the direction lengthwise of the track into precisely the proper position in that direction for machining at the machining station, and when said following part moves into guiding relationship with said opposed surfaces it holds the carrier in said last mentioned position.

23. Mechanism for positioning work for machining comprising a track leading to a machining station, a work carrier movable along the track to a machining station, resilient means on the work carrier receiving the work to be machined and automatically adjusting to irregularities in the surface of the workpiece to support the workpiece, means on the carrier accurately positioning the work relative to the work carrier, locking means on the resilient means limiting the movement of the resilient means after the work is positioned on the carrier, ways at the machining station generally alongside the track, a work carrier movable along the track to the machining station, means transferring the carrier from the track to the ways at the machining station to accurately position the work carried by the carrier for machining, and work-clamping means at the machining station engaging the workpiece to force the workpiece against the resilient means thereby maintaining the work against movement relative to the work station during machining.

24. Mechanism for successively positioning a workpiece at spaced-apart work stations comprising a track passing through each of successive work stations, ways at each work station generally parallel to the track, a self-propelled work carrier movable along the track from one work station to another, resilient means on the work carrier receiving the work to be machined to automatically adjust to irregularities in the surface of the workpiece, means on the carrier accurately positioning the work relative to the work carrier and means for transferring the carrier from the track to the ways at each machining station to accurately position the work carried by the carrier for machining, and returning the carrier to the track after completion of the work at the work station.

25. Mechanism for successively positioning a workpiece at spaced-apart work stations comprising a track passing through each of successive work stations, ways at each work station generally parallel to the track on opposite sides thereof, a self-propelled work-carrying car having a body and wheels adapted to run on the track, said body having a portion overhanging the ways and spaced above them when the wheels are in running position on the track, resilient means on the car body receiving the work to be machined and automatically adjusting to irregularities in the surface of the workpiece, means on the car body accurately positioning the work relative to the car body, means retracting the wheels upwardly relative to the car body to lower the overhanging portion of the body into contact with the ways, means on the carrier having opposed substantially parallel vertical surfaces normal to the length of the track and forming a guideway, and means at each work sta-

15

tion having a tapered portion movable in a plane substantially parallel to the vertical surfaces on the carrier and entering therebetween, whereby the carrier is moved lengthwise of the track into precise position for machining at the work station.

26. Mechanism for positioning work for machining comprising a track leading to a machining station, a work carrier movable along the track to the machining station, a plurality of hollow vertical sockets mounted on the work carrier, a piston in each of said sockets, each piston having a bevel face thereon, spring means on each piston tending to move it vertically upwardly in its socket, said pistons receiving the work to be machined and automatically adjusting against the spring means to irregularities in the workpiece, work-engaging means on the carrier engaging one end of the workpiece for rotation on a horizontal axis, screw means cooperating with the work-engaging means to move the work-engaging means in the direction of the axis of rotation to position the workpiece on the carrier, a second work-engaging means on the carrier at the opposite end of the workpiece engaging the workpiece, second screw means cooperating with the second work-engaging means moving said second work-engaging means vertically and horizontally, locking means on each vertical socket engaging the bevel face on the piston limiting the downward movement of the piston after the work is positioned relative to the carrier, ways at the machining station generally alongside the track means for transferring the carrier from the tracks to the ways at the machining station to accurately posi-
